UNITED STATES PATENT OFFICE.

ISAAC N. HOYT, OF AUGUSTA, WISCONSIN.

CAR-COUPING.

SPECIFICATION forming part of Letters Patent No. 281,271, dated July 17, 1883.

Application filed March 20, 1883. (No model.)

To all whom it may concern:

Be it known that I, ISAAC N. HOYT, a citizen of the United States, residing in Augusta, in the county of Eau Claire and State of Wisconsin, have invented a new and useful Improvement in Car-Couplings, of which the following is a specification.

My invention relates to improvements in the mechanism for coupling railway-cars, and relates to a class in which the cars are attached to one another by means of a link and pins; and the objects of my improvements are to construct a draw-bar or buffer in such a manner and with such a combination of parts as to hold the link and pin in such position when the cars are uncoupled that they will couple themselves when brought together, and to permit of such another arrangement of parts as to prevent coupling if it is desired to push the cars, and yet leave them in position to couple the next time they are brought together. I attain these objects by the mechanism illustrated in the accompanying drawings, in which—

Figure 1 is a vertical section on a line 1 and 2 of Figs. 2 and 4. Fig. 2 is an end view; Fig. 3, a side view of one buffer and vertical sectional view of the other in the act of coupling. Fig. 4 is a top view; Fig. 5, a vertical section in the act of holding the pin, the section being on line 1 and 2, Figs. 2 and 4.

Similar letters refer to similar parts throughout the several views.

The bar by which the freight-cars are drawn, which will be called hereinafter a "buffer," is in present practice provided with a recess in the outer end, which receives one end of a link. A hole is made vertically, through which a pin passes, as also through the interior of the link. The cars are attached by the link and the two pins. The cars when so attached have slack, to permit them to be started one at a time, and permits each car to sway sidewise. To permit the necessary slack and sway, the link must be loose around the pin and fit loosely in the recess in the buffer. When the cars are to be coupled, it is necessary to direct the link to its position in the recess of the buffer, and when they meet to drop the pin through. To permit the slack and sway, and yet couple automatically, I construct the buffer with a recess for the link and hole for the pin as at

present constructed, but opening into the recess from the rear I make a hole vertically through the buffer, the front and rear ends of which slant upward and backward. The sides 55 of the hole run longitudinally with the buffer, and are a less distance apart than the width of the link. In this hole I place a weight, B, free to slide up and down in it, and, guided by the slanting ends, recedes as it rises and advances as it falls. It is provided with a jaw at a, which, with the lower surface of the recess in the buffer, grasps the link C immediately behind the pin d, Fig. 1. The weight B has a slanting side, b, Fig. 3, which, when the link C 65 and pin D are both removed and the weight is resting on the bottom of the recess in the buffer, shuts partly over the upper hole for the pin and prevents the pin D, Fig. 3, from falling through. To the upper side of the weight 70 B, I attach a rod, c, having the same slant as the rear end of the weight, and forming a part of the weight. Over the hole in the buffer I place a cap, sufficiently concave on its lower surface to permit the weight to rise until the 75 lower edge of the jaw a, Fig. 1, is as high as the upper surface of the recess in the buffer, but having a hole through which the rod c may slide. To the pin D, Fig. 5, I hinge a dog, F, Fig. 5, near its upper end, of sufficient length 80 to reach to the rod c of weight B, when the pin rests in the upper hole in the buffer, as in Fig. 5.

It operates as follows: When it is desired to couple two cars, the link is placed in the recess in the buffer of one, Figs. 1 and 3. The link 85 is held horizontal by the jaw a of the weight B, resting on the end of the link back of the pin, as in Fig. 1. The other car-buffer is left with the weight B down, and the pin D in the upper part of the hole retained there by the 90 face b of the weight B, as in Fig. 3. When the cars meet, the link C, Fig. 3, enters the recess in the buffer and pushes the weight B, Fig. 3, backward and upward, releasing the pin D, which falls through the link.

Sometimes it is desired to push a car to some point and leave it, and also to leave it in position to couple on again. I accomplish this by the dog F, Fig. 5, attached to the pin D, Fig. 5, and the rod c of the weight B. The pin D 100 on the car to be pushed is raised out of the link and the foot of the dog placed against the

rod *c*, Fig. 5. The weight *B* may then be raised and lowered above the link without disengaging the pin; but if the link be removed, the weight *B*, Fig. 5, falls to the bottom of the recess in the buffer, carrying the rod *c* below the top of the plate *E*, disengaging the dog *F*, but retaining the pin by the face *b* in position to couple. The cap *E* serves as a guide for the rod *c* and also to protect the weight from the weather.

What I claim as my invention, and desire to secure by Letters Patent, is—

1. The combination, with the buffer, of the weight *B*, having a rod, *c*, the cap *E*, and the

pin *D*, having a dog, *F*, attached substantially as and for the purposes herein specified.

2. The combination, with the buffer having a slanting hole through it, the link, and coupling-pin, of the weight *B*, having jaw *a*, inclined face *b*, and rod *c*, and the protecting cap *F*, having a hole through the top thereof, the several parts constructed and arranged to operate substantially as herein shown and described.

ISAAC N. HOYT.
